UNITED STATES PATENT OFFICE.

ABRAHAM SONDACK, OF BRONX, NEW YORK.

RECEPTACLE FOR IRONING BOARDS.

Application filed May 22, 1926. Serial No. 110,839.

This invention relates to improvements in ironing boards, and has particular reference to a clothes receptacle therefor.

- An object of the invention is to provide 5 an improved board of simple and practical construction, the supporting framework of which carries a receptacle utilized as a depository for clothes and the like while the board is in use.
- 10 Another object is to so mount the receptacle upon the foldable framework of the board that said receptacle may be collapsed when the framework is folded, thus permitting the entire structure to occupy a minimum 15 space.

The above and other objects will appear more clearly from the following detail description, when taken in connection with the accompanying drawings, which illustrate a 20 preferred embodiment of the inventive idea.

In the drawings—

Figure 1 is a side elevation of the board in operative position;

25 Figure 2 is a vertical transverse section on the line 2—2 of Figure 1; and

Figure 3 is a side elevation of the board in its folded or inoperative position.

The foldable framework of the board comprises the standards 4 and 5 each of which 30 includes vertical side members which may be connected at their upper ends, the side members of the standard 5 being joined at their upper ends by a strap 6 pivoted thereto and to which one end of the board 7 is secured. Said board is provided adjacent its 35 other end with a stop 8 which may be engaged with the upper end of the standard 4 when the board is in operative position to aid in retaining the same in such position and also prevent collapsing of the standards. 40 The lower end of the standard 4 and the upper end of the standard 5 are connected by diagonal braces 9 pivotally joined to said standards. Adjacent the lower ends of the 45 braces 9 the same have pivoted thereto at 10 the sections 11 of horizontal braces. One extremity of each section 11 is pivoted to one end of a link 12, the other end of which is pivoted to the adjacent side member of 50 the standard 4. The opposite end of each section 11 is pivoted at 13 to the adjacent end of a shorter section 14 which combines with the section 11 to form the horizontal brace. The other end of said section 14 is 55 pivotally connected at 15 to the adjacent side member of the standard 5 and is pro-

vided adjacent said pivot with a stop 16 engageable with said standard to maintain the sections 11 and 14 in longitudinal alignment and prevent their swinging downwardly about the pivot 13 from the operative position shown in Figure 1. The sections 11 and 14 may, however, swing upwardly about the pivots 10, 13 and 15 to permit of folding the framework. This folding 60 operation is accomplished by first lifting the free end of the board 7 to disengage the stop 8 from the standard 4 whereupon the standard 5 may be moved over toward the standard 4 with the diagonal braces 9 swinging 65 about the pivot connection therefor at the lower ends of the latter standard. At the same time, the sections 11 and 14 will break upwardly at the pivots 13 and the sections 11 will swing about the pivots 10 70 with the links 12 moving toward a vertical position such as shown in Figure 3. When the framework is folded to the position in the latter figure, the board 7 may be made to assume a vertical position alongside the 75 standard 4 and the board and its supporting structure will then be in completely folded position.

The standard 5 may have pivoted thereto 80 an auxiliary board 17 which may be maintained in horizontal position by stop pins 18 engageable with the braces 9 adjacent the upper ends thereof.

The board further comprises a collapsible 85 receptacle which, in its operative position, will be located directly below the board 7 and be adapted to receive articles of clothing and the like while the board is in use. This receptacle includes a bottom consisting of sections 19 and 20 secured to the sections 11 90 and 14, respectively, of the horizontal braces, the sections 19 and 20 being preferably provided with side flanges 21, as best shown in Figure 2, which are fastened to the respective sections of said braces. The receptacle 95 further includes the side members 22 which are hinged only to the side flanges 21 of the section 19, as indicated at 23. The side members 22 are adapted to be collapsed into the bottom of the receptacle, as shown in 100 dotted lines in Figure 2, so that said side members will not interfere with the folding 105 of the framework of the board.

To support the side members 22 in opposite position, the receptacle further 110 includes end members 24 which are fixedly secured to the standards 4 and 5 and are

provided in their edges with notches 25 for receiving the free ends of latches 26 pivoted to the side members 22. Thus when the latches are engaged in the notches in the end members 24 it will be apparent that the side members will be maintained in a vertical position and that to collapse said members said latches need only be detached from the end members whereupon the side members 10 may be swung downwardly about their hinges 23 and into the bottom of the receptacle. When thus positioned the receptacle will not interfere with the folding of the framework as described and since said side members 22 are not connected to the sections 14 of the horizontal braces, it will be apparent that said braces may be broken at the pivotal points 13, as previously set forth.

What is claimed is:

1. An ironing board including a foldable supporting framework, comprising standards and braces connecting the same, a collapsible receptacle carried by said framework and including side, end and bottom wall members, the side members being hinged to said bottom member and the end members of said receptacle being fixedly secured to said standards.

2. An ironing board including a foldable supporting framework, comprising standards and braces connecting the same, a collapsible receptacle carried by said framework and including side and bottom wall members, the side members being hinged to 30 said bottom member, end members for said receptacle fixedly secured to said standards, and latching means for supporting said side members in operative position.

3: An ironing board including a foldable supporting framework, comprising standards and braces connecting the same, a collapsible receptacle carried by said framework and including side and bottom members, the side members being hinged to said bottom member, end members for said receptacle fixedly secured to said standards and having notches therein, and latches pivoted to said side members and engageable in said notches to retain said side members in operative position. 40

4. An ironing board including a foldable supporting framework, comprising standards, horizontal braces connecting said standards and formed in sections pivotally connected together, a receptacle including a bottom member secured to the sections of said horizontal braces, side members hinged to said bottom member, and end members for said receptacle fixedly secured to said standards. 50

5. An ironing board including a foldable supporting framework, consisting of standards, horizontal braces including pivotally connected sections having pivotal connections with said standards, a receptacle including a bottom member consisting of sections carried by the sections of said horizontal braces, side members for the receptacle hingedly connected to only one of the sections of said bottom member, and end members for the receptacle fixedly secured to said standards. 60

In testimony whereof I have affixed my signature.

ABRAHAM SONDACK.
